J. F. CASEY

MOLD

Filed Dec. 26, 1923

INVENTOR
JOHN F. CASEY
BY C. F. Blake
ATX.

UNITED STATES PATENT OFFICE.

JOHN F. CASEY, OF PORTLAND, OREGON.

MOLD.

Application filed December 26, 1923. Serial No. 682,759.

To all whom it may concern:

Be it known that I, JOHN F. CASEY, a citizen of the United States, residing at Portland, county of Multnomah, State of Oregon, have invented certain new and useful Improvements in Molds, of which the following is a specification.

My invention relates to molds in general, and particularly to mold devices adapted for moulding concrete building brick and the like, the object being to provide a device whereby concrete brick may be moulded in sand molds.

I accomplish the above object by means of the construction illustrated in the accompanying drawing, which is a part of this application for Letters Patent, like characters of reference indicating like parts throughout the several views thereof, and in which:

Figs. 1, 2, 3, 4 and 5 are sectional perspective views of my device as it appears in the various steps of its use; Fig. 6 is a perspective view of the pattern board; 25 and Fig. 7 is a perspective view upon an enlarged scale of one of the filling funnels.

In general my device consists of a pattern board having a plurality of patterns mounted thereupon, a mold box adapted 30 to embrace said patterns, a follow plate adapted to lie between said pattern board and said box and to receive each of said patterns through a suitable respective orifice therein, and a funnel board provided 35 with a plurality of funnels, one such funnel to each of said patterns.

The pattern board, which is illustrated in detail in Fig. 6, is a flat board 8 provided with a plurality of patterns 9, and ears 10 disposed upon opposite edges of said board, and within which ears are secured dowel pins 11. Handles 12 are also provided for lifting said pattern board, which handles may conveniently be mounted upon said 45 ears, as shown.

A follow board, preferably of iron plate, 13, is provided, with orifices adapted to receive said patterns 9, the edges of each of said orifices being beveled towards the lines 50 of juncture of said patterns with the pattern board 8, as shown in Figs. 1 and 2. Said follow board is provided with ears 14 adapted to register with the ears 10 upon the pattern board 8, and to receive the 55 dowel pins 11 through orifices in said ears 14.

A mold box 15 is provided to embrace the patterns 9, said box having an open top and bottom, and being provided with ears 16 adapted to register with the ears 14 and 60 10 previously described, and to receive the dowel pins 11 through suitable orifices in said ears.

A funnel plate 17 is also provided, having a plurality of funnels thereupon, there being one such funnel for each pattern 9 upon the pattern board 8. Said funnel board 17 is also provided with ears 18 adapted to register with the ears 14 and 16 previously described, and is provided with dowel pins 70 19, adapted to fit into the orifices in the ears 14 and 16.

In use the pattern board 8 is deposited upon the moulding floor or table with the patterns pointing upward, and the box 15 placed thereupon. Sand is thereupon rammed into the box 15, and a board 20 placed on the top of the box 15. Said cover 20 and the pattern board 8 are then clamped together by clamps well known 75 to the foundry art, and therefore not illustrated in the drawing, and the whole turned over into the position shown in Fig. 2. The pattern board 8 is then removed together with the attached patterns 9, leaving the 80 device as shown in Fig. 3, with the follow board on the top. The funnel board is then placed in position as shown in Fig. 4, and the liquid concrete poured into the 85 molds through the funnels.

Each of the funnels is constructed to fit into its respective mold leaving a space therebetween of substantially a constant width, and the body 21 of the funnels is substantially of the same shape as that of the mold. Each funnel is secured to the funnel board with the body below said board, and with an upward flaring top 22 projecting above the board, as shown in detail in 95 Fig. 7. Adjacent the lower end of each funnel slots 23 are provided through which the liquid concrete is deposited within the mold. The purpose of such funnels is to introduce the concrete into the mold in a manner that will not break down the surface 100 of the mold. Liquid concrete is poured into the funnels until it stands slightly above the top of the follow plate 14, whereupon the funnel plate with the funnels attached thereto is slowly withdrawn, letting the liquid concrete settle into the molds. After 110 the funnel board has been removed the tops

of the contents of the molds are slicked off smooth with the top of the follow board, and then said follow board and the box 15 are removed, leaving the sand mold with the 5 moulded product therein upon the board 20, as shown in Fig. 6.

My device may be made of any size, and constructed of any materials deemed convenient and suitable for a device of this 10 character, and while I have illustrated and described a form of construction found desirable in materializing my invention, I 15 wish to include in this application all mechanical equivalents and substitutes that may fairly be considered to come within the scope and purview of my invention as defined in the appended claims.

Having disclosed my invention so that others may be enabled to construct and to 20 use the same, what I claim as new, and desire to secure by Letters Patent is:

- 25 1. In a mold: a mold board having a plurality of patterns secured thereupon; and a follow board adapted to lie upon said pattern board, and having orifices therein to receive said patterns, each of said orifices having beveled edges adapted to coincide with the line of juncture of the respective pattern with said pattern board.
- 30 2. In a mold: a pattern board having a

plurality of patterns secured thereupon; a follow board adapted to lie upon said pattern board, and having orifices therein to receive said patterns, each of said orifices having beveled edges adapted to coincide with the line of juncture of the respective pattern with said pattern board; and a funnel board adapted to lie upon said follow board, and having a plurality of funnels thereupon, each funnel being adapted to enter the mold left by the withdrawal of the pattern board and its attached patterns. 35

40 3. In a mold: a plurality of molds; a funnel board adapted to cover said molds; a plurality of funnels upon said funnel board, each of said funnels comprising a body of substantially the shape of the mold into which it is adapted to extend and provided with orifices at the lower end thereof, and an upwardly flaring top. 45

50 In witness whereof I claim the foregoing as my own I hereunto affix my signature in the presence of two witnesses, at Portland, county of Multnomah, State of Oregon, this 9th day of Aug., 1923.

JOHN F. CASEY.

Witnesses:

L. J. ROBINSON,
C. F. BLAKE.
